CLAIM

The ornamental design for a glove with zig zag texture as shown and described.

DESCRIPTION

FIG. 1 is a front elevation view showing the new, original, and ornamental design of a glove with zig zag texture, the square area indicated by broken lines and the number seven correspond to the close-up view shown in FIG. 7; FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 shows a close-up view corresponding to the square area indicated by broken lines in FIG. 1; and,

FIG. 8 shows a cross sectional view of the square area shown by FIG. 7 as viewed in the direction of the arrows shown in FIG. 7.

The broken lines pattern areas near the upper wrist shown in FIGS. 1-4 illustrate portions of the article and form no part of the claimed design. All other broken lines demarcate the close-up view and form no part of the claimed design.
